[57] ABSTRACT

A transparent colored film product, which becomes clear and colorless at image areas when heated thermographically, contains a p-quinoneimine color body and a mild reducing agent.

7 Claims, No Drawings

HEAT-SENSITIVE COPY-SHEET

This invention relates to thermographic copying, wherein a copy of a differentially radiation-absorptive original is made on a heat-sensitive copy-sheet product held in heat-conductive contact therewith by briefly exposing the original to intense infra-red radiation. In one aspect the invention relates to novel heat-sensitive copy-sheet products. In a particularly important aspect the invention relates to copy-sheet products useful in making negative color projection transparencies.

Negative-acting copy-sheets adapted for making color projection transparencies have previously been described. In U.S. Pat. No. 3,609,360 the decolorization involves the heat-induced decomposition of a colored reaction product of components including a volatile acid which is then released to the atmosphere. U.S. Pat. No. 3,684,552 somewhat analogously uses an amine-reactive color body and a heat-decomposable salt of a nitrogenous organic base.

The present invention employs a different class of color bodies and a different reaction system, and provides a heat-sensitive copy-sheet product which when locally heated, as in the thermographic copying process, is converted from a highly colored to a substantially colorless, and preferably a clear and transparent, form at the heated image areas without release of volatile decomposition products.

The heat-sensitive copy-sheet products of the present invention contain p-quinoneimine color bodies which undergo decolorization when heated at thermographically induced temperatures in reactive association with a mild reducing agent. The color body is supplied in a matrix of film-forming binder as a coating on a paper, transparent film or other carrier or as a self-supporting film. The reducing agent may be incorporated in the same matrix, or in an adjacent stratum supported on the carrier or on a separate carrier. A particularly useful structure comprises a transparent flexible film carrier coated with a first stratum of p-quinoneimine color body in a transparent binder and overcoated with a mild reducing agent in a separate binder. Brief heating of the film product causes migration of at least one of the reactants and results in a decolorization of the color body at the heated area.

Reducible p-quinoneimine color bodies which are useful in the preparation of heat-sensitive copy-sheets of the invention include those having the structural formula

wherein Ar is an aromatic radical and the R, R', R'' and R''' substituent radicals may be hydrogen, halogen, alkyl, alkoxy or amido, or wherein substituent radicals on adjacent carbon atoms may complete a fused polycyclic or heterocyclic ring, all as exemplified by the following illustrative compounds:

- 2-methyl-N(p-morpholinophenyl)-p-
benzquinoneimine
2,6-dimethyl-N(p-morpholinophenyl)-p-
benzoquinoneimine
2,6-dichloro-N(p-morpholinophenyl)-p-
benzoquinoneimine

- 2-chloro-2'-methyl-N,N-diethylindoaniline
2-chloro-N(p-diethylamino-2-methylphenyl)-p-
benzoquinoneimine
2-acetamido-N,N-diethylindoaniline
3-methoxy-2'-methyl-N,N-diethylindoaniline
N-(1-naphthyl)-p-benzoquinoneimine
N-(2-naphthyl)-p-benzoquinoneimine
N-(p-acetylphenyl)-p-benzoquinoneimine
2,6-dichloroindophenol sodium salt
2,3',6-trichloroindophenol sodium salt
2,6-dibromoindophenol sodium salt
2,5-dibromo-N(2,4-dibromophenyl)-p-
benzoquinoneimine
N-(p-diethylamino-2-methylphenyl)-1,4-
naphthoquinoneimine
N-(p-diethylamino-2-methylphenyl)-5,8-
quinolinoquinoneimine
N-(2,4-diamino-5-methylphenyl)-p-
benzoquinoneimine trihydrate indoferron
N-(p-diethylamino-2-methylphenyl)-2-carboxylic-1,
4-naphthoquinoneimine
N-(p-dimethylaminophenyl)-1,4-
naphthoquinoneimine
The following mild reducing agents have been found
useful:
2,5-dihydroxybenzoic acid
chlorohydroquinone
2,5-dichlorohydroquinone
30 tetrachlorohydroquinone
bromohydroquinone
diiodohydroquinone
phenylhydroquinone
2,6-di-t-butylhydroquinone
2,5-di-t-butylhydroquinone
35 2,5 bis(1,1-dimethylpropyl) hydroquinone
2,5-di-pentylhydroquinone
trimethylhydroquinone
t-butylhydroquinone
methylhydroquinone
catechol
3-methylcatechol
4-methylcatechol
4-t-butylcatechol
3-isopropylcatechol
4-isopropylcatechol
45 4-t-octylcatechol
3,5-diisopropylcatechol
3,6-diisopropylcatechol
3,5-di-t-butylcatechol
3-t-butyl-5-methylcatechol
3-methyl-5-t-butylcatechol
3-methyl-5-octylcatechol
3-methoxycatechol
50 tetrabromocatechol
resorcinol
4-ethylresorcinol
4-n-propylresorcinol
4'-phenylazoresorcinol
4,6-dichlororesorcinol
o-hydroxyethylresorcinol
2,6-dihydroxybenzoic acid
2,4-dihydroxybenzaldehyde
2', 6'-dihydroxyacetophenone
2', 4', 6'-trihydroxyacetophenone
60 methyl gallate
butyl gallate
1,2,3-trihydroxybenzene

2',3',4'-trihydroxydecanophenone
 1,2,4-trihydroxybenzene
 2,4,5-trihydroxybutyrophenone
 o-aminophenol
 m-aminophenol
 p-aminophenol
 4-amino-2,6-dibromophenol
 4-amino-2,6-dichlorophenol
 2-amino-4-chlorophenol
 3-diethylaminophenol
 2,4-diaminophenol
 p-benzylaminophenol
 4-amino-2,5-dimethylphenol
 6-amino-m-cresol
 4-amino-m-cresol
 5-amino-1-naphthol
 m-hydroxydiphenylamine
 4'-aminoacetanilide
 2,6-diaminotoluene
 3,4-diaminotoluene
 1,4-diaminobenzene
 1,8-diaminonaphthalene
 tetramethyl-1,4-diaminobenzene
 furoin
 1,3-dihydroxyacetone
 L-ascorbic acid
 arabo-ascorbic acid
 4-methoxy-1-naphthol
 2-methoxy-1-naphthol
 1-amino-2-methoxynaphthalene
 2,3-naphthalene diol
 1,4-naphthalene diol
 5,8-dihydroxy-1,4-dihydro-2-methylnaphthalene
 1-naphthol

Strong reducing agents may also be used in some cases, in particular with the lower molecular weight color bodies and in constructions involving separate sheets, but are presently of only minor interest.

Binder systems may include such polymeric materials as polystyrene, styrene-acrylonitrile or styrene-acrylate copolymers, styrene-butadiene-acrylonitrile terpolymers, polyvinylchloride, vinyl chloride-vinyl acetate copolymers, vinylidene chloride-acrylonitrile or vinylidene chloride-vinyl acetate copolymers, polyacrylates, polyvinyltoluene. These polymers are moisture-resistant, being incapable of absorbing more than about one percent of water, and are preferred as contributing to the stability of the sheet materials during prolonged storage both before and after imaging.

The concentration of color body in the color stratum must be sufficient to impart a distinctive color but excessive amounts require undesirably large quantities of reducing agent, or excessive heating, or may reduce the transparency of the stratum and accordingly are to be avoided. Similarly, the amount of reducing agent available per unit area should be sufficient to react with all of the color body but need not be greatly in excess of that amount and, at least for single sheet projection transparencies, should be well within the range of full compatibility with the binder so that the stratum remains clear and non-light-diffusing.

The following Examples, in which all proportions are in parts by weight unless otherwise indicated, will further illustrate the practice of the invention which however is not to be construed as limited thereto.

EXAMPLE 1

A carrier film of 2 mil (0.05 mm.) ethylene glycol terephthalate polyester film primed with a trace coating of terpolymer primer is supplied with first and second reactant strata, with intermediate and final drying, as follows:

10	First stratum	
	2-chloro-2'-methyl-N,N-diethylindoaniline	1.6
	polyvinyl chloride-acetate ("Geon 421" resin)	11.8
	methyl ethyl ketone	69.3
	toluene	17.3
	dry at 180°F.	
	coating weight, dry, 2.5 g./sq. m.	
15	Second stratum	
	tertiarybutylhydroquinone	4.4
	polyvinyl butyral ("Butvar B-76" resin)	2.6
	nitrocellulose (½ sec.)	10.4
	methanol	82.6
	dry at 130°F.	
	coating weight, dry, 4.0 g./sq. m.	
20		
	The resulting sheet is transparent and blue in color.	
	It is placed against an original consisting of line drawings in black ink or a white paper and the composite is passed through a thermographic copy machine. The	
25	blue color disappears at the heated image areas. The sheet is placed on an overhead projector and is found to project a white image on a blue background. The appearance of the sheet and of the projected pattern remains unchanged during several hours of continuous	
30	projection.	

EXAMPLE 2

A solution containing

35	2-chloro-2'-methyl-N,N-dimethylindoaniline	0.6
	polyvinyl chloride-acetate ("VYNS" resin)	12.0
	methyl ethyl ketone	96
	toluene	12

is applied to thin polyester film and dried in an oven at 150°F. The dried coating is a deep blue in color and weighs 4.7 g./sq. m.

A solution containing

45	tertiary butyl hydroquinone	1
	½ sec. nitrocellulose	1
	polyamide ("Elvamide 8061" resin)	1
	methanol	97

is applied over the first coating at approximately the same wet coating thickness and is promptly dried in the 150°F. oven.

The resulting film is imaged in a thermographic copying machine to provide a negative color projection transparency as in Example 1.

EXAMPLE 3

60	First trip solution	
	2-chloro-2'-methyl-N,N-diethylindoaniline	0.25
	polystyrene ("Styron 690" resin)	7.5
	methyl ethyl ketone	42.5
	Second trip solution	
	tertiarybutyl hydroquinone	0.67
	13.5% solution of nitrocellulose in methanol	8
	13.5% solution of polyvinylbutyral in ethanol	2

Coating weights and procedures are as described in previous Examples. By thermographic copying a good negative color projection transparency is obtained.

EXAMPLE 4

First trip solution			
2-chloro-2'-methyl-N,N-diethylindoaniline	0.50		
vinyl chloride-acetate polymer ("Geon 421" resin)	7.5		
acetone	67.5		
Second trip solution			
t-butyl hydroquinone	1.3		
ethyl cellulose ("G-200" resin)	5		
ethanol	95		

Procedures and results are generally as described in preceding Examples.

EXAMPLE 5

First trip solution			
2-chloro-2'-methyl-N,N-diethylindoaniline	0.25		
vinyl chloride-acetate polymer	5		
methyl ethyl ketone	36		
toluene	9		
Second trip solution			
t-butyl hydroquinone	5		
methanol	35		
acrylate latex ("Rhoplex AC-61"), 45% NVM	36		
colloidal silica ("Ludox AM")	24		

Introduction of silica improves the resistance of the coating to surface picking and roughening during thermographic copying without appreciably reducing the clarity. Procedures and results are substantially as described in the preceding Examples.

EXAMPLE 6

Solution A			
N-(p-acetylphenyl)-p-benzoquinoneimine	0.4		
polyvinyl chloride-acetate ("VYNS" resin)	5		
methyl ethyl ketone	40.5	35	
toluene	4.5		
Solution B			
methyl hydroquinone	10		
polyvinyl chloride-acetate ("VYHH" resin)	2		
polyvinyl butyral ("Butvar B-76" resin)	10		
methyl ethyl ketone	76		

Solution A is applied to thin 2 mil (0.05 mm.) polyester film from a coater bar at a 2 mil (0.05 mm.) orifice and the coating is dried. Similarly, solution B is coated at the same thickness on a separate portion of 1 mil (0.025 mm.) film and the coating is dried. The two sheets are placed in face-to-face contact. The composite is placed against a printed original which is then subjected to brief exposure to intense infra-red radiation. The second sheet is peeled from the first, leaving a projection transparency with clear image areas and yellow background areas.

EXAMPLE 7

Solution A			
2-chloro-2'-methyl-N,N-diethylindoaniline	0.25		
polyvinyl chloride-acetate	5		
methyl ethyl ketone	40.5		
toluene	4.5		
Solution B			
t-butyl hydroquinone	10		
ethyl cellulose ("T-100" resin)	10		
ethanol	80		

The solutions are coated on separate sheets of thin polyester film, and the two sheets are combined and processed, as in Example 6, with similar results.

As an alternate structure a second sheet is prepared from a solution of ten parts of t-butyl hydroquinone

and 9 parts of polyvinyl butyral resin in 91 parts of acetone, coated on thin (21 1/2 lb/ream) glassine. Substantially the same results are obtained.

EXAMPLE 8

First coat

2-chloro-2'-methyl-N,N-diethylindoaniline	0.25
polyvinyl chloride-acetate	10
methyl ethyl ketone	90

15 Second coat

4-methoxy-1-naphthol	15
polyvinyl butyral	30
titanium dioxide pigment	10
ethanol	222

The mixture is homogenized by prolonged milling in a ball mill, applied over the first coat at the same orifice, and dried.

The coated sheet provides a white image against an opaque blue background when used as a thermographic copy-sheet.

EXAMPLE 9

30 First coat

methyl gallate	3
ethyl cellulose	5
ethanol	95

Coated on 2 mil (0.05 mm.) polyester film at 2 mil (0.05 mm.) orifice, and dried.

Second coat

2,6-dichloroindophenol sodium salt	0.3
polystyrene-acrylonitrile ("Tyril 860" resin)	15
acetone	85

Coated over first coat at 2 mils (0.05 mm.) and dried.

The product provides a negative color projection transparency by thermographic copying.

EXAMPLE 10

55 To a solution of 0.08 part 2,6-dichloro-N(p-morpholinophenyl)-p-benzoquinoneimine and 5 parts of a copolymer of methyl methacrylate and ethyl acrylate in 20 parts of methyl ethyl ketone is added 0.45 part of 2,5-dihydroxybenzoic acid and the mixture is quickly coated on transparent film and dried. The sheet provides a color projection transparency when printed thermographically but is found to have short shelf life, the initial magenta color gradually fading during storage. Some improvement in performance may be achieved by increasing the proportion of binder but these sheets are generally less permanent and hence less desirable than those in which the two reactants are in separate strata.

EXAMPLE 11

First solution	
N-(p-diethylamino-2-methylphenyl)-5,8-quinolino quinoneimine	0.25
polyvinyl chloride-acetate	6
methylethyl ketone	44
nickel resinate	q.v.
Second solution	
tertiarybutyl hydroquinone	0.67
13.5% solution of nitrocellulose in methanol	8
13.5% solution of polyvinylbutyral in ethanol	2

Sufficient nickel resinate solution is added in the first solution to change the color from blue to green. The solution is coated on polyester film at 0.05 mm. and dried, and is overcoated with an equal wet thickness of the second solution which is also promptly dried. Under thermographic copying procedures the sheet provides a color projection transparency with clear image areas and a green background.

EXAMPLE 12

First coat	
N-(1-naphthyl)-p-benzoquinoneimine	0.3
polyvinyl chloride-acetate	0.5
methylethyl ketone	25
toluene	24.5
Coated at .05 mm. on polyester film and dried.	
Second coat	
stannous chloride	1
vinyl acrylate latex ("Ucar 360") (55% NVM)	50

Coated over the fully dried first coat at same wet thickness and promptly dried.

A clear image on a red background is obtained by thermographic copying procedures, but the sheet deteriorates rapidly on aging, particularly under humid storage conditions.

The thermographic copying procedure is conveniently carried out on commercially available thermographic copying machines such as the "Secretary" brand machines sold by Minnesota Mining and Manufacturing Co. and in which a copying temperature within the range of 100°-160°C. is usually attained.

Simple contact heating with heated type or stylus is also effective and permits more accurate determination of temperature if desired for comparison or test purposes.

5 What is claimed is as follows:

1. Colored sheet material capable of undergoing localized loss of color when thermographically heated in presence of a reducing agent and containing a p-quinoneimine color body in a film-forming binder, 10 wherein said color body has the structure

wherein Ar is an aromatic radical and the R, R', R'' and R''' substituent radicals may be hydrogen, halogen, alkyl, alkoxy or amido, or wherein adjacent substituent radicals may constitute a fused polycyclic or heterocyclic ring.

2. Sheet material of claim 1 disposed in face-to-face relationship with a second sheet containing said reducing agent.

3. Sheet material of claim 1 wherein is included a said reducing agent.

4. Sheet material of claim 3 wherein said reducing agent is a hydroquinone, catechol, resorcinol or trihydroxy-aromatic mild reducing agent.

5. Sheet material of claim 3 wherein said reducing agent is contained in said binder.

6. Sheet material of claim 3 wherein said reducing agent is contained in a different film-forming binder as 35 a separate stratum adjacent the stratum containing said color body.

7. Sheet material of claim 6 wherein said strata are supported on a thin flexible transparent film carrier.
